UNITED STATES PATENT OFFICE.

CHARLES COLLÉ, OF LILLE, FRANCE, ASSIGNOR TO HECTOR LAHOUSSE & CO., OF SAME PLACE.

GALVANIC BATTERY.

SPECIFICATION forming part of Letters Patent No. 403,253, dated May 14, 1889.

Application filed October 1, 1888. Serial No. 286,849. (No model.) Patented in Belgium June 8, 1888, No. 82,112, and in England June 18, 1888, No. 8,905.

To all whom it may concern:

Be it known that I, CHARLES COLLÉ, engineer, (of the firm of Hector Lahousse & Co.,) a citizen of the French Republic, and a resident of Lille, in the Republic of France, have invented certain new and useful Improvements in Electric Batteries, (for which I have obtained Letters Patent in Belgium, No. 82,112, dated June 8, 1888, and in Great Britain, No. 8,905, dated June 18, 1888,) of which the following is a specification.

This invention relates to an improved two-liquid battery, in which a novel liquid is employed to act on the zinc in the porous vessel with a view of obtaining, by the aid of improved arrangements of the parts situated externally to the said porous vessel, a very constant current of great power at a relatively low cost.

And in order that my said invention may be fully understood, I shall now proceed more particularly to describe the same, and for that purpose shall refer to the several figures on the annexed sheets of drawings, the same letters of reference indicating corresponding parts in all the figures.

Figure 1 of the accompanying drawings represents a battery according to this invention in vertical section. Fig. 2 is an end elevation of the same. Fig. 3 is a plan. Fig. 4 represents a perspective view of the top of the battery, showing the arrangement of the parts; and Fig. 5 represents an element with two carbons for a large battery.

The battery according to this invention is made with an external vessel of a material proof against the action of the concentrated nitric acid which it contains and inclosing a porous vessel, B, containing a special liquid for acting on the zinc, C. The space between the two vessels is filled with granular carbon, D, packed around electrodes E of retort-carbon, forming the positive pole, the whole being covered by a layer of pitch, H, or other suitable material, through which the porous vessel, the carbons, and two glass tubes, F F', project. The tube F is employed for introducing the concentrated nitric acid, while the

air escapes by the tube F'. After this operation both the tubes are hermetically sealed, 50 to prevent any escape of hyponitric vapors.

The action on the zinc is obtained by means of a solution composed of about thirty-five parts, by weight, (say thirty-five grams,) of bisulphate of mercury and thirty-five parts, by weight, (thirty-five grams,) of concentrated nitric acid in about one thousand parts, by weight, (one liter,) of water. In preparing this solution the bisulphate must be mixed with three hundred parts (thirty centiliters) 60 of water, in the first instance shaking or agitating it until the solution is of the color of yolk of eggs, and then continuing the agitation while the nitric acid is being poured in and until the liquid becomes clear. The solution thus prepared is poured into the porous vessel, in the interior of which the zinc is afterward placed, being allowed to rest upon a collar, G, of porcelain or other inoxidizable material, which also acts as a cover for the 70 said porous vessel. The battery thus constituted is used in the same way as an ordinary battery, over which it possesses the following advantages, namely:

First. The current is very regular and not 75 liable to sudden accessions of force. The intensity of the current is about two volts and the quantity from about six and a half to seven ampères for a minimum period of action of about sixty hours.

Second. The zinc is equally acted on at all points, is consumed very slowly and with great regularity, and never requires taking out of the liquid.

Third. The residues are zinc salts and free 85 mercury. These products are valuable, and may be collected either for the purpose of being regenerated or for sale. In either case their commercial value is an important set off against the cost of working the battery.

Fourth. The battery requires but little attention to keep it in working order compared to a Leclanché battery, for example.

Fifth. Owing to the small proportion of the salt of mercury employed in one charge, and 95 also owing to the long duration of each charge,

the working expense is very low, especially when the value of the residues is taken into account.

In fact, in general terms a battery according to this invention is economical, powerful, constant and regular, and demands very little care.

I do not limit myself to the precise forms, proportions, or materials illustrated by way of example in the accompanying drawings, and the proportions of the ingredients employed may evidently be varied according to circumstances without affecting the principle of my invention; but

15 What I claim is—

In a two-liquid battery with a porous cup, the combination of a solution of bisulphate of mercury and concentrated nitric acid in suitable proportions and a zinc plate in one cell, with granular-retort carbon and ordinary carbons and nitric acid in the other cell, substantially as herein set forth.

In testimony that I claim the foregoing as my invention I have signed my name, in presence of two witnesses, this 18th day of Sep- 25

CHARLES COLLÉ.

Witnesses:

GUSTAVE PIERRIER,
EMILE NYUBS.
